UNITED STATES PATENT OFFICE.

MASAYOSHI KOJIMA, OF LOS ANGELES, CALIFORNIA, ASSIGNOR OF ONE-THIRD TO
TOICHIRO SAKURAI, OF LOS ANGELES, CALIFORNIA.

ENVELOP.

1,159,686.

Specification of Letters Patent.

Patented Nov. 9, 1915.

Application filed January 30, 1915. Serial No. 5,238.

To all whom it may concern:

Be it known that I, MASAYOSHI KOJIMA, a subject of the Emperor of Japan, residing at Los Angeles, in the county of Los Angeles and State of California, have invented a new and useful Envelop, of which the following is a specification.

This invention relates to envelopes and has particular reference to a safety envelop so 10 designed and constructed that it cannot be surreptitiously opened without detection.

Another object of the invention is to provide an envelop having no intricately formed parts and being of a very practical 15 construction so that it may be easily folded into shape to receive a letter.

With these and other objects in view, the invention consists of certain novel features of construction, combination and arrangement of parts as will be hereinafter fully 20 described, illustrated and claimed.

Referring to the drawings: Figure 1 is a view of the envelop blank extended. Fig. 2 is a plan view showing the blank partly folded. 25 Fig. 3 is a rear elevation of the envelop in condition to receive a letter. Fig. 4 is a rear elevation showing the envelop sealed. Fig. 5 is an enlarged fragmentary transverse sectional view on the plane of line 5—5 of Fig. 30 4. Fig. 6 is a similar view showing the various flaps spaced from one another. Fig. 7 is a fragmentary plan view of an extended flap showing a slightly modified construction. Fig. 8 is a fragmentary view showing 35 a modified form of bottom flap.

In the drawings, 1 designates the face wall or body of the envelop having the end flaps 2, the bottom flap 3 and the closing flap 4 secured to the edges thereof. The bottom 40 flap 3 is provided with a sealing tongue 4', which may be of any desired shape, but which is here shown as being semi-ovicular and formed by slitting the flap arcuately as indicated at 5. The inner edge of the tongue 45 is left attached to the flap and the inner face of the tongue is covered with gum or glue.

A triangular tab 6 is formed on the outer edge of the bottom flap 3 and this tab carries a preferably triangular tongue 7 which is 50 formed by incising the flap as at 8. It will of course be understood that this tongue may be made in other shapes if desired. The tongues 4' and 7 are so positioned with respect to one another that when the tab 6 is

folded against the flap 3, the two tongues will 55 be opposed to one another. The base of the tab 6 is longer than the edge of the flap 3 to which it is attached, and therefore the corner portions 9 which are gummed, project beyond the edges of the bottom flap, and 60 are adapted to be passed through slits 10 opening upon the upper edges of the end flaps 2.

In bending the blank to form the envelop, the end flaps are first folded against the 65 inner face of the wall 1, then the tab 6 is folded against the inner face of the bottom flap 3 and finally the bottom flap 3 is folded so as to overlap the inner edges of the end flaps 2. The bottom flap is secured to the 70 edges of the end flaps 2 by the gum indicated by the numeral 11, and the corner portions 9 extend through the slits 10 and are stuck to the inner faces of the flaps 2, as previously mentioned. These corner portions 75 make it practically impossible for a person desiring to clandestinely open the envelop to insert a sharp or flat instrument between the end flaps and bottom flap and move it between the stuck portions of the 80 flaps so as to separate them without injuring the corner portions in such fashion as to indicate that the envelop had been opened. The sealing flap 4 is formed with the two 85 outwardly converging slits 12, which form a centrally located triangular tongue 13 which is gummed on its inner side for adherence to the triangular tongue 7 when the envelop is sealed. After sealing flap 4 has been secured in position to close the envelop, the 90 tongue 4' is folded against the outer face of the flap and stuck thereto by the mucilage preferably carried on the tongue. The tip of the tab 6 may be provided with mucilage as indicated at 6' to secure the tab to the flap 95 3 when it is folded thereagainst. When the envelop is entirely sealed up the tongues 13, 4' and 7 the corner 9 will catch any instrument which is used in an endeavor to open the envelop without detection, and when the 100 instrument strikes these projections it will injure them so that the envelop may not again be sealed in such fashion as not show that it has been tampered with.

In the modified form shown in Fig. 7, 105 tongues 14 are provided on the edges of the bottom flap 15 to take the place of the corner portions 9 and the tabs 6. In this form, the

triangular tab 16 does not extend beyond the side edges of the bottom flap 15.

Fig. 8 is a fragmentary view showing a modified form of bottom flap which may be used in place of the bottom flaps 3 and 15 previously described. The flap 17 of Fig. 8 is provided with a gummed tongue 18 having its line of connection with the flap perforated as at 19 and said flaps also formed 10 with ears 20 which are perforated at their point of connection and indicated at 21. The flap is triangular and the apex portion 22 is bent on the line 23 to lie against the inner side of the flap. This apex portion is 15 provided with a tongue 24 as shown. The ears 20 may be made of any length desired and may be of such size as to extend the whole length of the edges to which they are attached.

20 What I claim is:

1. An envelop having a face wall, end flaps folded thereagainst, said end flaps having slits in their upper edges, a bottom flap secured to the face wall, a tab carried by the 25 bottom flap and being folded against the inner face thereof, said tab having corner portions projecting beyond the bottom flap and being extended through said slits in the end flaps, and a closing flap to fold against and be secured to the bottom and end flaps.

2. An envelop comprising a face wall, end flaps secured to said face wall, a bottom flap secured to the face wall, a tab carried by the 35 bottom flap to fold against the inner face thereof, said tab having a tongue formed therefrom, the bottom flap being provided with a tongue opposed to the tongue of the tab, and a sealing flap formed with incisions

to provide a tongue, said tongue being adapted to coact with said first mentioned tongue. 40

3. An envelop comprising a face wall, end flaps, a bottom flap and a sealing flap, the end flaps being each provided with a slit, the bottom flap being provided with a tab lying against the inner side thereof and having corner portions projecting through said slits, the bottom flap being also provided with a tongue hinged thereto along one edge, the tab having a tongue hinged thereto along one edge and opposed to said first mentioned 50 tongue, and the sealing flap being formed with a tongue adapted to fold into alignment with said first mentioned tongue.

4. An envelop comprising a face wall end flaps having slits therein carried by the face 55 wall, a bottom flap carried by the face wall, a tab carried by the bottom flap and adapted to fold against the inner face thereof, a tongue carried by said tab, a tongue carried by the bottom flap and engaging the first 60 named tongue, tongues projecting from opposite sides of the bottom flap and adapted to extend through said slits, a closure flap carried by the face wall and adapted to fold against and be secured to the bottom and end 65 flaps, and a tongue carried by said closure flap and registering with the first and second named tongues.

In testimony whereof, I have hereunto set my hand at Los Angeles, California, this 70 12th day of January, 1915.

MASAYOSHI KOJIMA.

In presence of—

LORA M. BOWERS,

ANNA F. SCHMIDTBAUER.
